CLAIM

The ornamental design for a trocar handle, as shown and described.

DESCRIPTION

FIG. 1 is a front perspective view of a trocar handle showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof;

FIG. 8 is an enlarged view of a portion of the trocar handle taken in FIG. 1;

FIG. 9 is a section view taken along line 9-9 in FIG. 2; and, FIG. 10 is an enlarged section view of a portion of the trocar handle taken in FIG. 9.

The broken lines shown in FIGS. 1-2 and 4-10 illustrate portions of the trocar handle that form no part of the claimed design. The broken lines shown in FIGS. 1 and 9 illustrate call out boxes that show the areas where the enlarged portions in FIGS. 8 and 10 are taken from. The dash-dot-dash broken lines illustrate a boundary and form no part of the claimed design.
